UNITED STATES PATENT OFFICE.

JOHN A. DAY, OF SANTA CLARA, CALIFORNIA.

REVERSIBLE OFFSET FOR PLOWS.

1,262,182.

Specification of Letters Patent.

Patented Apr. 9, 1918.

Application filed January 10, 1918. Serial No. 211,160.

To all whom it may concern:

Be it known that I, JOHN A. DAY, a citizen of the United States, residing at Santa Clara, in the county of Santa Clara and State of California, have invented certain new and useful Improvements in Reversible Offsets for Plows, of which the following is a specification.

My invention relates to reversible offset for plows and more particularly to that class of plow known as orchard plows.

The objects of my invention are, first to provide a reversible offset for plows of simple and durable construction, capable of being used in orchards for plowing close to the trees, or in any place where close plowing may be required.

Second to provide a reversible offset for plows that may be offset at the inner end 20 of the plow beam of a plow, and a reversible offset that may be quickly adjusted as the operator may require.

Third to provide a reversible offset for plows that will draw the plow straight in its 25 offset position on either side of the plow beam.

A still further object of my invention is generally to improve this class of devices so as to increase their utility, durability and 30 efficiency.

Further objects and advantages will appear in the following description, it being understood that various changes in form, proportion and minor details of construction 35 may be resorted to within the scope of the appended claim.

For a full understanding of the invention and the merits thereof, reference is to be had to the following description and accompanying drawings, in which—

Figure 1 is a plan view of my improvement in reversible offset for plows.

Fig. 2 is a side view of Fig. 1.

Fig. 3 is a detail side view of the reversible offset bar for plows.

Fig. 4 is a detail side view of the adjustable rear tension rod.

Corresponding and like parts are referred to in the following description and indicated in all the views of the drawings by the same numerals.

My improved reversible offset for plows forming the subject matter of the present invention comprises an angle iron 1, fastened near the rear end of a plow beam 2 by bolts 3, connected to angle iron 1 is reversible offset bar 4 by bolt 5 and opening 5^a, bar 4 being turnable on bolt 5.

Angle irons 6 are shown fastened to each side of reversible offset bar 4 by rivets 7, and are for the purpose of holding offset bar 4 in its offset position to plow beam 2 on either side thereof. At, or near the outer end of offset bar 4 is draw pin 8 projecting out a distance from each side of bar 4 and 65 is an integral part of bar 4 connecting with draw bar 9 by a plurality of openings 10.

Reversible tension rod is shown at 11, connected to offset bar 4 by bolt 12 and openings 12^a and 12^b, the inner end of reversible tension rod 11 being connected to angle iron 13 by screw threaded portion 14 and adjustable machine nuts 15; angle iron 13 being held in place near the rear end of plow beam 2 by bolts 16.

Tension rod 11 is turnable in angle iron 13 to the right or left as required.

The operation of my reversible offset for plows is as follows:—

Offset bar 4 is placed in position on the 80 desired side of the plow beam 2 and connected with draw bar 9 by draw pin 8 with the desired opening 10 in draw bar 9; this adjustment will draw the plow straight in its offset position, when the draft is applied 85 to the forward end of the bar 9, making the working of the plow much easier on the operator and the horses drawing the plow, when plowing close to the trees or in any place where close plowing may be required. 90

Having thus described my invention, what I claim as new and desire to secure by Letters Patent, is—

In a reversible offset for plows, the combination of an angle iron fastened near the 95 rear end of a plow beam, means by which the angle iron is fastened to the plow beam, a reversible offset bar connected to the angle iron, and means by which the offset bar is turnable thereon, angle irons fastened, 100 one on each side of the offset bar, adapted to hold the offset bar in its offset position,

a draw pin which is an integral part of the offset bar projecting out a distance from each side thereof, a draw bar having a plurality of openings therein, adapted to engage said draw pin, means for attaching the draft to the forward end of the draw bar, a reversible tension rod, an angle iron, and means of fastening the angle iron to the rear portion of the plow beam, means

by which the tension rod is connected to 10 the angle iron and to the offset bar.

In testimony whereof I affx my signature in the presence of two witnesses.

JOHN A. DAY.
